schaft mit beschränkter Haftung, a corpora-
tion of Germany

Application June 9, 1937, Serial No. 147,330
In Germany May 18, 1936

4 Claims. (Cl. 137—156.5)

This invention relates to atmospheric pressure responsive devices of the type used in apparatus for controlling the fuel feed for aircraft engines or other internal combustion engines which operate at varying altitudes. The adjusting members of said devices consist of a plurality of diaphragm capsules, sensitive to variations in atmospheric pressure, which are mounted in series in a casing for longitudinal movement therein. 10 The diaphragm capsules hitherto usual in these devices can be easily injured by the vibrations occurring in the operation of the engine. These vibrations affect the exactitude of the control and cause bending stresses at the fastening points of 15 the capsules which greatly reduce the strength and durability of the device.

These drawbacks are avoided according to the invention by the adjusting member acting on the fuel feed consisting of several diaphragm capsules, each guided so as to be longitudinally displaceable. By this means the further substantial advantage is obtained, that a large adjusting movement that is equal in length or extent to the sum of the movements exerted by the individual diaphragm capsules is available for influencing the fuel feed. The controlling device can thus, by means of the invention, be arranged in a comparatively small space without a power amplifier operated from an external auxiliary source of power, for instance oil under pressure, having to be employed to obtain the desired extent of movement.

A further substantial advantage consists in the feature that if a leakage occurs only one diaphragm capsule becomes inoperative. The small irregularity in the working of the apparatus thereby occurring can be easily compensated for, and the internal combustion engine can be kept in further operation until the defective diaphragm capsule can be changed on the occasion of a longer stoppage of the vehicle. Preferably, the diaphragm capsules are mounted so as to be longitudinally displaceable loosely within a common guide, and operatively connected together or held in place by a spring which acts at the same time as a return force. In view of the fact that the capsules are usually made of very thin metal and are subjected in use to considerable vibration and bending stresses, guide means are provided to support and guide the capsules and to protect them against wear.

In the accompanying drawing—

Fig. 1 is a sectional view of an example of construction of the invention, and

Fig. 2 shows a somewhat different construction of the diaphragm capsules shown in Fig. 1.

A cylindrical sleeve 11 bounded by walls 12 and 13 is arranged in a casing 10, in which sleeve four diaphragm capsules 15 are mounted so as to be longitudinally displaceable. These are operatively connected together and to the wall 12 by a spring 17 by the intermediary of a lever 16. The lever 16 is pivotally mounted in two supports 18 provided on the sleeve 11, and carries at its lower 10 angularly bent and forked end the fulcrum 19 of a two-armed lever 20, which is carried through two slots 14 in the sleeve 11. This lever has a cranked part for the spring 17, and is connected by its upper end to a link 21 pivotally mounted 15 on the controlling member 22 of an injection pump of known type, while the other lever arm, made forked and provided with a guide slot 23, engages with a driving member 24 that is provided on a bolt 26 connected to a diaphragm 25. 20 The diaphragm 25 and the bolt 26 with a spring 27 serving for the guidance of the bolt, are arranged in a casing member 30 flanged on to casing 10 and in open communication with it, and provided with a cover 31 shutting off the dia- 25 phragm. In the hollow interior of this cover two springs 28 and 28' serving as return force springs are arranged. A pipe for the offtake of pressure leading to the air induction pipe of the internal combustion engine is connected to a pipe-con- 30 nection 29.

The sleeve 11 enclosing the diaphragm capsules is mounted in the casing 10 so as to be displaceable, so as to be able to vary the adjustment of the controlling rod 22, if required, independently of the action of the diaphragms 15 and 25. For this purpose, a lever 33 having a guide slot is employed, which is secured to a shaft 34 passing through the casing 10 and provided with an adjusting lever 35. Lever 33 acts on a bolt 32 40 provided on the wall 12 of the sleeve 11, and the freedom of movement of this lever is limited by a stop-pin 36. The casing 10 can be connected by a face 40 to an injection pump of known type, having a controlling member, indicated by 22, 45 which controls the injection amount. Instead of the cylindrical sleeve, a cage consisting of separate guide-bars may also be employed.

The mode of working of the apparatus is as follows:

If the air supply to the engine is throttled, a vacuum occurs in the pressure feed pipe connected to the pipe socket 29, and thus also in the interior of the cover 31. The diaphragm 25 is in this case forced into the interior of the cover by 55

atmospheric pressure until the springs 28 and 28' have compensated for the difference in pressure acting on the diaphragm and the opposing force of the spring 27. By this movement the lever 20 is rocked about the axis 19 and the controlling rod 22 pulled into a position in which the feed of fuel is reduced. When the external air pressure sinks, the diaphragm capsules expand and move the fulcrum 19 to the left. In this case also the lever 20 and thus also the controlling rod 22 are brought into a position reducing the feed of fuel. In order to adopt the particular amount of fuel delivered to the fuel requirement of the engine, the abutments of the springs 17, 27 and 28' are arranged so as to be adjustable.

Of course, a controlling of the mixture dependent on the changing working conditions may also be obtained by a throttle valve arranged in the air induction pipe being movably connected to the lever 20, and this lever in case of need, furthermore can act on a controlling member governing the fuel feed and thus corresponding to the controlling rod 22.

The diaphragm capsules shown in Fig. 2 differ from those in Fig. 1, simply by the feature that a threaded bolt 41 and a nut 42 by which the capsules can be connected together are respectively secured to their elastic flexible walls. Centering rims 43 are provided on the nuts on which guide-plates 44 provided with a corresponding bore are placed, the edges 45 of which plates overlap the diaphragm capsules. These guide-plates are gripped, when each two adjacent diaphragm capsules are assembled, between the shoulder formed in making the centering rim and the foot of the threaded bolt.

When assembled, the guide plates 44 are arranged between the capsules 15 and extend over the edges thereof to support and guide them in sleeve 11 and also to protect them against wear due to vibration and relative movement between these parts. This is important, particularly when the capsules are made of relatively thin metal because, in use, these parts are subjected to considerable vibration and bending stresses.

We declare that what we claim is:

1. In apparatus of the character described, an atmospheric pressure responsive device comprising a casing, a plurality of diaphragm capsules sensitive to variations in atmospheric pressure mounted in series in said casing for longitudinal movement therein, each of said capsules being provided with guiding means arranged between adjacent capsules and projecting over the edges of its respective capsule, said guiding means be-

ing capable of axial movement together with its respective capsule within the common casing, whereby contact of the edges of said capsule with the casing is prevented.

2. An atmospheric pressure responsive device 5 comprising a casing, a plurality of diaphragm capsules influenced by variations in atmospheric pressure mounted in series for longitudinal displacement in said casing, means for connecting together adjacent capsules whereby the expansion and contraction movements of the capsules are translated from one capsule to the other, each capsule being provided with guiding means carried by said connecting means and projecting over the edges of its respective capsule, said guiding means being capable of being moved axially together with its respective capsule within the common casing, whereby contact of the edges of said capsule with said casing is prevented.

3. An atmospheric pressure responsive device 20 comprising a casing, a plurality of diaphragm capsules influenced by variations in atmospheric pressure mounted in series for longitudinal displacement in said casing, connecting members for connecting together adjacent capsules, a 25 centering rim being provided on one of each pair of connecting members, and a guide member for each capsule mounted on the centering rim and held in position thereby, each guide member projecting over the edges of its respective capsule 30 and being movable with its respective capsule within the casing whereby said capsules are centrally supported and guided for longitudinal displacement in said casing and contact of the edges of said capsules with said casing is prevented.

4. An atmospheric pressure responsive device comprising a casing, a plurality of diaphragm capsules influenced by variations in atmospheric pressure mounted in series for longitudinal displacement in said casing, means for connecting together adjacent capsules whereby the expansion and contraction movements of the capsules are translated from one capsule to the other and guide members one for each capsule carried by 45 said connecting means and movable with its respective capsule within the common casing for supporting and guiding said capsules in said casing, said guide members each comprising a disc having an edge at right angles thereto which at 50 least partly encloses its respective capsule and prevents contact of the edges of the capsule with said casing.
